(57) **CLAIM**

The ornamental design for a trim element for a ceiling system, as shown.

DESCRIPTION

FIG. 1 is a perspective view of a trim element for a ceiling system.

FIG. 2 is an end elevational view thereof, the opposite end being identical thereto.

FIG. 3 is an enlarged view as seen along 3—3 of FIG. 2; and, FIG. 4 is an enlarged view as seen along 4—4 of FIG. 2. The broken lines shown in FIGS. 1—4 are for illustrative purposes only and form no part of the claimed design.
